UNITED STATES PATENT OFFICE.

EDWARD M. CURRIER, OF EVERETT, MASSACHUSETTS, ASSIGNOR TO JOSIAH M. READ, OF SAME PLACE.

DESIGN FOR A HANDLE FOR POKERS OR LIKE IMPLEMENTS.

SPECIFICATION forming part of Design No. 16,786, dated July 13, 1886.

Application filed April 22, 1886. Serial No. 199,850. Term of patent 7 years.

To all whom it may concern:

Be it known that I, EDWARD M. CURRIER, of Everett, in the county of Middlesex and State of Massachusetts, a citizen of the United States, have invented a new and useful Improvement in Design for Handles to Pokers and other Like Implements, of which the following is a full, clear, and exact description, reference being had to the accompanying drawings, forming a part of this specification, in explaining its nature.

The nature of the design is best ascertained by reference to the drawings, in which—

Figure 1 is a side elevation of the handle, and Fig. 2 is a plan view thereof.

It is adapted especially as a handle for a poker or other implement having a metal extension from one end.

The essential features of the design are the smooth upper section, A, and the corrugated lower section, B, formed to inclose the space C.

It will be seen that the upper section or part, A, of the handle is smooth upon its upper surface, and that it is somewhat rounded upon its edges, and that it turns at its end to unite with the lower section, B, which is formed to present a wavy outline.

The two sections A B unite and form the extension of the implement.

Having thus fully described my invention, I claim and desire to secure by Letters Patent of the United States—

A design for a handle for pokers or other like implements, having a section, A, with a smooth surface, and shaped substantially as shown, and the corrugated section B, substantially as shown and described.

EDWARD M. CURRIER.
